(57) CLAIM

The ornamental design for a wagering device display, as shown and described.

DESCRIPTION

FIG. 1 is a perspective view of the wagering device display; and,

FIG. 2 is a front elevational view of the wagering device display.

Broken lines showing the portions of the wagering device on the exterior and interior of the display are for illustrative purposes only and form no part of the claimed design.

1 Claim, 1 Drawing Sheet
